UNITED STATES PATENT OFFICE.

WILLIAM B. HODGE, OF CHARLOTTE, NORTH CAROLINA, ASSIGNOR TO PARKS-CRAMER COMPANY, OF FITCHBURG, MASSACHUSETTS, A CORPORATION OF MASSACHUSETTS.

AIR CONDITIONER.

Application filed March 18, 1924. Serial No. 700,124.

This invention relates to air conditioning and particularly to apparatus for humidifying air.

In direct humidification of the air in rooms, by means of humidifying heads mounted in the rooms, high rates of humidification are often found impracticable because of poor air circulation. This leads to localized super-saturation of the air and local precipitation.

The apparatus forming the subject matter of the present application involves the traversing of the humidifier so that it discharges a blast of highly humidified air into the air of the room at progressively changing places, either by traversing the humidifier or by progressively changing its orientation.

The invention lends itself readily to practice by the use of a simple oscillating fan or other commercial traversing fan as the air propelling element of the humidifier. The moisture is sprayed into the air current created by the fan and the traversing action of the fan causes the air current to carry this moisture in various directions successively, so that the moisture continually reaches fresh bodies of air. For this reason a higher water rate is possible than can be used with a similar fan fixed in position or direction.

To secure simple regulation, I provide means for actuating the controlling mechanism by power derived from the fan, and preferably from the traversing movements thereof. This permits the use of a light and simple hygrostatic device, which is never subjected to the load shifting the controlling mechanism, but serves merely to position stops or the like so as to apply the power of the fan.

Various embodiments of the apparatus are possible, but I prefer and illustrate one making use of a simple oscillating electric fan, in conjunction with an aspirating water sprayer.

In the drawings:—

Fig. 1 is a side elevation of the complete device.

Fig. 2 is a rear view thereof.

Fig. 3 is a section on the line 3—3 of Fig. 2.

The oscillating fan includes a pedestal base 6, and an oscillating head 7, mounted at 8 on the base 6 so as to turn on a vertical axis. The head 7 encloses an electric motor

which drives the fan 9, and simultaneously, 55 through a mechanism of familiar form indicated generally at 10, causes the head 7 to oscillate on its vertical axis when the fan is running.

Formed on the base 6 are brackets 11 60 which carry a water pipe 12 and an air pipe 13. The air pipe 13 is provided with a stop, valve 14 whose stem 15 carries an arm 16. This swings through a relatively small angle between open and closed positions as clearly 65 shown in Fig. 3. The fan 9 is protected by the usual guard 17 which carries at its centre in front of fan 9 an atomizing nozzle 18 having a flexible tubular connection 19 with water pipe 12 and a second flexible tubular connection 20 with air pipe 13. The air blast through nozzle 18 draws water through pipe 12 and connection 19, and sprays this water into the air current produced by fan 9.

In the case of the nozzle described, the water head is insufficient to discharge water through nozzle 18 except when the air blast is acting. Valve 14 thus serves to stop and start the water spray from nozzle 18. While this valve controls the air blast directly and the water only indirectly, as explained, it is in effect a means for controlling the water spray. Although I prefer the atomizing nozzle described, it is apparent that other sprays might be used, and that certain of 85 them might require direct control of the water in ways familiar to those skilled in the art. The construction illustrated thus is typical of controllable water sprays generally, and in a narrower sense is explicit as 90 to the preferred construction.

To actuate the valve 14 I make use of an actuator device swinging with head 7 and set by a hygrostat. A bracket 21 on head 7 carries a cross-bar or spreader 22. A hygroscopic member 23 consisting of strands of silk or the like has one end connected at 24 to one end of spreader 22, and the other end connected through swivel 25, and adjusting screw 26 to the other end of spreader 100 95 22. Screw 26 has a knurled head 27, by which it is adjusted and has a graduated dial 28 on which the adjustment is indicated by index 29.

Mounted near the mid-length of member 105 23 is a clip 30 connected by links 31 with a lever 32. This lever is fulcrumed between its ends on bracket 21 by means of a screw

33. Swiveled in the ends of lever 32 are sleeves 34 through which extend rods 36 having heads 37 at their upper ends. The rods control the positions of respective latch members 38 each of which is guided in a guide member 39 carried on head 7. The latch members 38 are free to move vertically but not to rotate and each is beveled at its lower end as shown at 40.
- 10 The rods 36 are connected to respective latch members 38 by threads 41, and by turning the rods the latch members may be adjusted. This adjustment may be so made that one latch member 38 moves into position to engage lever 16 practically as soon as the other member 38 clears it, giving the closest possible regulation, or a lag may be caused by so adjusting the latch members that there is a considerable range of motion 20 of lever 32 in which neither member 38 engages. The structure is obviously susceptible of modification.

The structure described is simple and largely self-contained. The regulating 25 mechanism is positive in action and may be applied to existing fans without requiring any very important changes.

While these structural features are of great practical importance, the device gains 30 its greatest practical value from the fact that it operates according to the method set forth, i. e., it serves to project a highly humidified air blast continually into fresh and relatively arid portions of the surrounding air. So far as the method is concerned, the path of the traversing fan is not limited 35 to changes of orientation, and I contemplate the use in practicing my method of various types of traversing fan having translatory movement of considerable range.

What is claimed is:

1. In a humidifier, the combination of a fan, automatic means for traversing said fan; and pneumatically actuated atomizing means for spraying water into the air current produced by said fan.
2. In a humidifier, the combination of a fan; automatic means for traversing said fan; and a pneumatically actuated atomizing water nozzle mounted to travel with said fan and arranged to direct its spray into

and in the general direction of the air current produced by the fan.

3. In a humidifier, the combination of a rotary fan; a device for oscillating said fan; a single power means for rotating said fan and actuating said oscillating means; and means for producing an atomized water spray in the air current leaving said fan.

4. In a humidifier, the combination of a rotary fan; a device for oscillating said fan; power means for rotating said fan and for actuating said oscillating means; and a pneumatic aspirating spray nozzle mounted to oscillate with said fan and to direct its spray in the general direction of the current produced by the fan.

5. In a humidifier, the combination of a fan; means for driving and simultaneously traversing said fan; means for spraying water into the air current produced by said fan; means for controlling said water spray; a hygostat; and stops arranged to be set by said hygostat; and operative alternatively in different settings to actuate said controlling means, through the traversing movements of said fan.

6. In a humidifier, the combination of a fan; means for driving and simultaneously traversing said fan; means for spraying water into the air current produced by said fan; means for controlling said water spray; a hygostat; and mechanism set by said hygostat, and arranged to apply the power of said fan driving means to actuate said spray controlling means in accordance with the varying condition of said hygostat.

7. In a humidifier, the combination of a fan; means for driving and simultaneously traversing said fan; means including an aspirating air blast for spraying water into the air current produced by said fan; means for controlling said air blast; a hygostat; and mechanism set by said hygostat, and arranged to apply the power of said fan driving means to actuate said air blast controlling means in accordance with the varying condition of said hygostat.

In testimony whereof I have signed my name to this specification.

WILLIAM B. HODGE.
